DESIGN FOR A COMBINED BOTTLE, APPLICATOR, AND CONTAINER THEREFOR

Evelyn Crosby Grullemans, Mentor, Ohio

Application April 20, 1939, Serial No. 84,438

Term of patent 14 years

To all whom it may concern:

Be it known that I, Evelyn Crosby Grullemans, a citizen of the United States, residing at Mentor, in the county of Lake and State of Ohio, have invented a new, original, and ornamental Design for a Combined Bottle, Applicator, and Container Therefor, of which the following is a specification, reference being had to the accompanying drawing, forming a part thereof.

Fig. 1 is a plan view of the combined bottle, applicator, and container therefor showing my new design;

Fig. 2 is a side elevational view thereof; and
Fig. 3 is a perspective view thereof with the cover removed and the contents of the container withdrawn.

I claim:

The ornamental design for a combined bottle applicator, and container therefor, substantially as shown and described.

EVELYN CROSBY GRULLEMANS.
